BOILER CLEANER

Norman L. Snow, New Canaan, Conn., and Frank Bowers and Curtis L. Howse, Detroit, Mich., assignors to Diamond Power Specialty Corporation, Detroit, Mich., a corporation of Michigan

Application August 28, 1924, Serial No. 734,746
Renewed November 29, 1932

19 Claims. (CL 122—391)

The invention relates to boiler cleaners and has for its object to provide apparatus for cleaning the tubes and other parts of boilers.

In the drawings:—

5 Figure 1 is a top plan view partly in section showing the blowers applied to a locomotive boiler;

Figure 2 is a side elevation thereof;

10 Figure 3 is a sectional view showing a blower in inoperative retracted position;

Figure 3a is a detail sectional view along 3a—3a of Figure 3;

15 Figure 4 is a view along the line 4—4 of Figure 3;

Figure 5 is a view corresponding to Figure 3 showing the blower in projected operative position;

20 Figure 6 is a section of a blower operated by a prime mover;

Figure 7 is an end elevation of the blower shown in Figure 6;

25 Figure 8 is a view along the line 8—8 of Figure 6.

Referring to Figure 1 of the drawings 10 indicates a locomotive boiler having the cab 11, boiler tubes 12 and boiler tube sheet 13. For cleaning these tubes there are located at the sides of the boiler preferably extending through the water legs 14, a pair of blowers 15. These blowers are located a suitable distance from the tube sheet 13 with their nozzles 16 directed toward the tube sheet. Each blower has a connection with a steam supply by a pipe 17, the steam supply being controlled by valves 18 conveniently located preferably in the cab. The operating rods 19 are formed with suitable handle portions 20 and are operably connected with the blowers as herein-after set forth.

Referring to Figure 3, rock arm 21 is adapted 40 to be reciprocated with the pivot shaft 22 by the operating rod 19 and handle 20. While the arm is shown as manually operable it is obvious that the same may be automatically operated. The forward end of shaft 22 carries the pinion 23 keyed to the shaft and meshing with the broad face gear 24 carried within the housing 25. The housing 25 is provided with a forward part 26 which is fixed within the sleeve 27 in the water leg 14. The housing also has a wall 28 providing a bearing for the hollow rod 29 the rear end of which carries the gear 24. The forward end of rod 29 carries the blower head 30 on which is mounted the nozzle 31 formed with bevel gear 32. Bevel gear 33 meshes with the gear 32 and 50 is carried by shaft 34 housed within and fric-

tionally carried by rod 29. The rear end of the shaft 34 has keyed thereto the pawl wheel 35 engaged by the pawl 36 pivotally mounted on the face of the gear 24. The shaft 34 frictionally carries the segment 37 upon which is mounted the pawl 38 also engaging the wheel 35. The housing 25 is provided with the slot 39 and in the slot the heads of the set screws 40 and 40' are adapted to operate. The set screws may be located in any of the openings 41 in the segment 37 so as to limit the movement of the latter and vary the increment of advance of the blower nozzle as will be later apparent.

The spring 42 bears at its forward end against the stationary wall 28 and at its rear end acts upon spacing sleeve 43 and thrust bearing 44 to normally retract the parts to the position shown in Figure 3. Between the part 26 and sleeve 27 air passages 27' are provided to afford air circulation to cool the blower.

The blower head 30 shown in Figures 3, 5 and 6 is provided at the forward end with a protecting heat-resisting cap 45 which is removably fastened to the blower head by pins 45a. This cap may be formed of any one or combination of a number of different heat resisting materials, examples of which are chromium iron alloy and nickel chromium iron alloy. When the blower is not in use this cap practically seals the end of water leg sleeve 27. The blower head is also provided with steam ports 46 between radial arms 46' as best shown in Figure 3a and relief ports 47 in arms 46' the latter ports communicating with a passage 48, ports 49 and chamber 50. Plunger 51 is carried by the blower head 30. Passages 47a are fitted with pet cocks 47b for draining the blower body of condensate.

With the parts in position shown in Figure 3, the operation is as follows: Steam is admitted through the pipe 17 to the chamber 52, around plunger 51 to chamber 53, through ports 46 to the nozzle 31. The nozzle and ports restrict the flow of the steam so that the steam pressure will force the blower head outwardly carrying the parts to the position indicated in Figure 5. In this position the spacing sleeve contacts with the wall 28 to limit the outward movement of the parts. The outward movement of the blower head 30 carries with it rod 29 and shaft 34 with the wheel 35, pawls 36 and 38, segment 37 and gear 24.

Steam escaping past the rod 29 and into chamber 50 will pass through ports 49, passage 48 and outlet ports 47.

With the parts of the blower in the projected

position the rock arm 21 is reciprocated to oscillate pinion 23 and gear 24. When the rod is moved to rock the gear 24 to the left or counter clockwise as shown in Figure 4, pawl 36 will rotate wheel 35. During this rotation the segment 5 37 which is frictionally carried on the shaft 34 also swings counter clockwise until set screw 40 contacts with the wall of the slot 39 adjacent thereto.

Throughout the remaining stroke of the rock 10 arm 21 pawl 38 permits the rotation of rod 34 and wheel 35 by the pawl 36. Thus, it will be noted that the blower head has been rocked with the nozzle without relative movement therebetween, the nozzle 31 directing its jet of steam 15 for the vertical height of the tube sheet.

When the rock arm 21 is operated to rotate the gear 24 in the opposite direction or clockwise as shown in Figure 4 said operation rotates blower head 30, shaft 34, segment 37 and wheel 20 35 all together until further rotation of the segment is prevented by reason of the set screw 40' contacting with the wall of the slot 39 adjacent thereto. For the remaining movement of the rock 25 arm 21 the pawl 38 prevents further rotation of the wheel 35 and shaft 34 and the gear 24 rotates the rod 29. During this remaining movement, therefore, the rod 29 will be rotated with respect to the rod 34 to act through the bevel gears 32, 33 to change the direction of the nozzle 31. By locating the set screws 40, 40' in the 30 various openings 41 the increment of advance of the nozzle may be varied. The parts are then in position for the next cycle which will include first 35 tracing a vertical path by the blower jet on the tube sheet substantially parallel with the preceding and spaced therefrom a distance determined by the relative movement between the gears 32, 33.

As the steam jets of the pair of blowers continue to sweep the face of the tube sheet vertically the change in direction of each nozzle directs the jet in horizontal increments across the tube sheet until it reaches the center where the continued revolving of the nozzle brings it back 40 to its original position. The nozzle thus has the combined movements imparted by the oscillation of rod 29 and the substantially horizontal movement of the nozzle with respect to the tube sheet.

In Figure 6 is shown a blower operated by a 50 prime mover. In this type of blower the steam supply pipe 17 communicates with the chamber 89^a formed in blower body 89 to which body is fixed the support 90. A prime mover such as the steam turbine 91 is supplied with steam by a pipe 92 communicating with supply pipe 17. The turbine is provided with suitable reduction gearing (not shown) and operates the bevel pinion 93 by a shaft 94 journaled at 55 95 in the support 90. Pinion 93 meshes with bevel gear 96 which is provided with a portion 97 carrying clutch elements 98. A disc 99 is fixed to a shaft 100 rotatably mounted with respect to the shaft 101. An arm 102 is connected to shaft 101 by pin 103 and has an end 60 bearing against projection 104 extending from the rear of the bearing support 90.

The disc 99 carries clutch elements 98' adapted to engage clutch elements 98 carried by the gear 96 when the blower is extended forwardly 70 in the position shown in Figure 6. Springs 105 normally urge the disc 99, shafts 100 and 101 rearwardly.

A sleeve 106 is fixed within support 90 and at the rear end is provided with a race 107 for the 75

anti-friction balls 108 held in place by race 109. The balls 108 take the thrust of the blower at the end of the forward stroke through the clutch and the gear 98.

Within the water leg 14 is a sleeve 110 housing the sleeve 112 and separated therefrom to permit circulation of air entering ports 111 in the blower body 89 for cooling the blower. Sleeve 112 is provided with ports 113 and 114 communicating with the steam supply 17.

The blower cylinder 115 is connected to rotate with the shaft 100 by bolts 116 extending through ribs 117. Suitable packing rings 118 are provided on the cylinder 115. At the rear of the blower cylinder a face 119 surrounds the sleeve 106 and is acted upon by steam from the port 114 to project the blower forwardly. Cylinder 115 is also provided with an elongated port 120 as shown in Figure 3.

The forward end of shaft 101 carries the bevel pinion 121 meshing with the bevel gear 122 carried by the blower cylinder. The bevel 122 is provided with a nozzle 123.

The sleeve 106 is provided with passages 106^a which communicate by ports 106^a with passages 100 101^a formed in shaft 100. Passages 106^a also communicate through port 106^b with passage 90^a formed in support 90. The passages and ports permit the escape of any condensate or steam that escapes past the moving parts.

A petcock 89^c may be provided for chamber 89^a by means of which condensate may be drained from this chamber. When the steam supply to pipe 17 is cut off springs 105 will return blower cylinder 115 to its normal retracted position at 110 which time substantially all of the steam behind face 119 will be forced out through port 114 into chamber 89^a, where it will condense and be drained out through cock 89^c. Any condensate remaining behind face 119 will be dried upon the 115 readmission of steam through port 114.

When steam is not being admitted to the blower, the blower nozzle 115, shafts 100, 101 carrying the disc 99 and arm 102 respectively are forced rearwardly by the springs 105 so that the 120 forward end of the blower cylinder will be housed within the sleeve 110. When steam is admitted to the blower through the supply pipe 17 it will enter the port 114 and act upon the face 119 of the blower cylinder to carry the parts forwardly as shown in Figure 6 compressing the 125 springs 105 and clutching the elements 98, 98' so that the turbine 91 will rotate the blower cylinder 115 through the shaft 100 and bevel gears 96, 93.

At the same time nozzle 123 will be carried forwardly into position to act upon the tube sheet. Port 120 of cylinder 115 will also now register with port 113 for a period of the rotation of the blower cylinder. The plane of rotation of the nozzle body 122 is preferably set at approximately 20° with the axis of the cylinder 115 and the nozzle 123 is also preferably set at approximately 20° inclination to the axis of rotation of the nozzle body so that in the position shown, the axis of the steam jet is at right angles to the axis of the cylinder. Upon rotation of the nozzle through an angle of 180° the nozzle will have moved outwardly through an angle of 40° whereby it is directed toward the center of the tube sheet. The ratio of the gears 121 and 121^a is such that for one revolution of the cylinder 115, the pinion 121 and shaft 101 being held fixed by reason of the arm 102 and projection 104, the nozzle body 122 will have rotated 180°.

A sleeve 106 is fixed within support 90 and at the rear end is provided with a race 107 for the 75

plus or minus one or more teeth depending on the increment of advancement desired.

As the blower cylinder rotates the port 120 will register with port 113, admit steam to the nozzle 123, during the time that the nozzle is directed toward the tube sheet. The blower will thus trace curvilinear paths of steam projected on the tube sheet and by reason of the bevel gears 121^a and 121 the nozzle 123 will be successively directed in different positions to trace paths of successively varying curvature on the tube sheet until the entire area of the tube sheet has been covered. After the blowers have covered the width of the tube sheet the steam supply is cut off and the spring 105 acts to automatically restore the parts to their original position.

For the sake of convenience, the invention has been described as being embodied in a device for cleaning boilers. It will be apparent, however, that the invention may be embodied in devices for cleaning apparatuses similar to boilers, and it is to be therefore understood that the term "boiler" wherever used in the specification or claims is to be construed as meaning a heat transfer apparatus or fluid heater of any character, while the term "boiler cleaner" is to be construed as meaning a cleaner for any such apparatus.

While it is preferred to use steam as the cleaning medium, other fluids such as air etc., could be used.

What we claim as our invention is:—

1. In combination a boiler cleaner having a blower head, a housing adjacent the fire box of the boiler and normally receiving the head of the boiler cleaner, means for projecting the head outside the housing and within the fire box and means formed of heat resisting material for protecting the end of the head.

2. A boiler cleaner having a blower head, and a cap formed of heat resisting material secured to the blower head.

3. In a boiler cleaner having a blower head, a cap formed of heat resisting material removably secured to the blower head.

4. In combination, a boiler having a water leg, a boiler cleaner having a blower head, a housing within the water leg normally receiving the blower head, a cap formed of heat resisting material secured to the end of the blower head and normally substantially closing the housing adjacent the fire box, and means for reciprocating the blower head in said housing.

5. In a boiler cleaner, the combination with a source of cleaning fluid and a discharge nozzle thereof, of a rotatable blower cylinder carrying said nozzle, a motor adapted to rotate said blower cylinder, means for introducing cleaning fluid to said nozzle during a portion of the rotation of said cylinder, cleaning fluid operated means for projecting said blower cylinder and nozzle, and means for retracting said cylinder and nozzle when the cleaning fluid supply is shut off.

6. In a locomotive boiler having a water leg and sleeved opening therethrough, a boiler cleaner having a blower cylinder rotatably and reciprocally mounted in said opening, a source of cleaning fluid, a discharge nozzle mounted in said blower cylinder, means for directing said nozzle to trace successive spaced paths with the cleaning fluid on the tube sheet of the boiler, cleaning fluid operated means for projecting said blower cylinder in the direction of the boiler fire box, means for retracting the cylinder when the cleaning fluid is cut off, a motor adapted to rotate the cylinder

and means for clutching the cylinder and motor together when the cylinder is projected.

7. In combination, a blower element having a discharge nozzle and an inlet port, a sleeve forming a bearing in which said blower element is longitudinally movable, said sleeve having a port in communication with a source of cleaning fluid, means for moving said sleeve to align the port in the blower element with the port in the said sleeve, and means for rotating said blower element to periodically register the port in the blower element with the port in the said sleeve whereby cleaning fluid is supplied to said blower element during a portion only of its rotation.

8. In a device of the character described, the combination with a movable blower element, means for supplying cleaning fluid to said blower element, and a power mechanism for moving said blower element, of means for establishing a driving connection between said power mechanism and said blower element when cleaning fluid is being supplied to said blower element.

9. In a device of the character described, the combination with a movable blower element, means for supplying cleaning fluid to said blower element, and means including a train of gears for moving said blower element, of a clutch adapted to form a driving connection between said train of gears and said blower element, and means for controlling the operation of said clutch in dependence upon the supply of cleaning fluid to said blower element.

10. In a soot blower, the combination with a casing, of a pipe rotatable and reciprocative in the casing, a nozzle on an end of the pipe projecting beyond the casing, means operable upon movement of the pipe to control the supply of pressure fluid to the pipe to be ejected from the nozzle, means including a turbine and reducing gearing actuated thereby for rotating the pipe continuously in one direction, a power driven motor for reciprocating the pipe in the casing to vary the projection of the nozzle with relation to the casing and to control the supply of pressure fluid to the nozzle, and a common control for the turbine and motor.

11. In a soot blower, the combination with a casing having a bearing and a passage intersecting the bearing, means for supplying pressure fluid to the passage, a pipe reciprocative and rotatable in the bearing and having a port to register with the passage, a nozzle on an end of the pipe projecting beyond the casing, means including a prime mover and transmitting mechanisms for rotating the pipe, a power driven motor for reciprocating the pipe to vary the projection of the nozzle with relation to the casing and also to move the port into and out of register with the passage, and a common control for the prime mover and the motor.

12. In a soot blower, the combination with a casing, of a pipe reciprocative and rotative in the casing, a nozzle on an end of the pipe projecting beyond the casing, means for supplying pressure fluid to the pipe to be ejected by the nozzle, a power driven motor for reciprocating the pipe to project the nozzle from a stored to a blowing position, mechanism for rotating the pipe to sweep the jet emitted from the nozzle, a second power driven motor for actuating the mechanism for rotating the pipe said motor being operatively coupled to said mechanism only when the pipe is in said blowing position, and means common to

- both motors for controlling the action of the same.
13. In a soot blower, the combination with a casing, of a pipe reciprocative and rotative in the casing, a nozzle on an end of the pipe projecting beyond the casing, means for supplying pressure fluid to the pipe to be ejected by the nozzle, a pressure fluid motor for reciprocating the pipe to project the nozzle from a stored to a blowing position, mechanism for rotating the pipe to sweep the jet emitted from the nozzle, a second pressure fluid motor for actuating the mechanism for rotating the pipe said motor being operatively coupled to said mechanism only when the pipe is in said blowing position, pressure fluid supply pipes communicating with both motors, and a common control valve for the supply pipes of both motors.
14. In a device of the character described, a movable blower element, means for supplying cleaning fluid to the blower element, power driven means for moving said blower element, a clutch for establishing a driving connection between said power driven means and said blower element only when cleaning fluid is being supplied to the blower element, and a common means for controlling the supply of cleaning fluid to the blower element and the supply of power to the power driven means.
15. In a fluid heater cleaner, a movable blower element, power driven means for moving said blower element means for supplying cleaning fluid to the blower element, means for operatively clutching said power driven means to said blower element only when cleaning fluid is being supplied to the blower element whereby the blower element is moved by said power driven means only when cleaning fluid is being supplied to the blower element, means controlling the supply of power to said power driven means, and means so interconnecting the operation of said last mentioned means and the operation of said clutching means that upon the actuation of the power control means the clutching means is automatically actuated.
16. In a fluid heater cleaner, a blower element mounted for longitudinal and rotative movements, means for moving said blower element longitudinally, means for rotating the blower element, and means controlling the flow of cleaning fluid to the blower element in dependence upon the longitudinal and rotative movements thereof and operating to supply cleaning fluid to said blower element during a portion only of its rotative movement.
17. In combination, a projectible and rotatable blower element, means for projecting said blower element, means for rotating the blower element, and means for limiting the supply of cleaning fluid to the blower element to periods when the blower element is projected and for controlling the flow of cleaning fluid to the blower element in timed relation to the rotation thereof and during a portion only of its rotative movement.
18. In a fluid heater cleaner, a projectible and rotatable blower element, means for rotating the blower element, fluid pressure actuated means for projecting the blower element, and means controlling the admission of cleaning fluid to the blower element in timed relation to the projection and rotation thereof said means operating to supply cleaning fluid to said blower element during a portion only of its rotative movement.
19. In a boiler cleaner unit, the combination with a movable blower element and a power mechanism for moving said blower element including a member fixed to said element and a cleaning fluid actuated motor, of means for establishing a driving connection between said member and said motor when cleaning fluid is supplied to said unit.
